UNITED STATES PATENT OFFICE

92,468

DESIGN FOR A DISPENSING VEHICLE OR ANALOGOUS ARTICLE

Monroe Harrison, Chicago, Ill.

Application August 22, 1933, Serial No. 49,083

Term of patent 3½ years

To all whom it may concern:

Be it known that I, MONROE HARRISON, a citizen of the United States, residing at Chicago, in the county of Cook and State of Illinois, have invented a new, original, and ornamental Design for a Dispensing Vehicle or Analogous Article, of which the following is a specification, reference being had to the accompanying drawings forming a part thereof.

In the drawings:

Fig. 1 of the drawings is a front perspective view of my improved dispensing vehicle with

an umbrella and its support omitted for convenience of illustration;

Fig. 2 is a similar view thereof including in addition an umbrella supported above the dispensing stand.

The dominant features of my invention are embodied in the dispensing container and in the awning.

I claim:

The ornamental design for a dispensing vehicle or analogous article, as shown and described.

MONROE HARRISON.
